COLOR TEACHING AID

Joseph Sallak, R.R. 1, Box 85,
Dyer, Ind. 46311

Filed Apr. 25, 1969, Ser. No. 16,896

Term of patent 14 years

Int. Cl. D19—08

U.S. Cl. D25—1

FIG. 1 is a plan view of a color teaching aid showing my new design; and

FIG. 2 is a front elevational view of the same.

The bottom of the design is identical in outline with the top thereof; and the side surfaces are identical and vertical.

I claim:

The ornamental design for a color teaching aid, as shown.
